S. SHETTER.

Horseshoe Machine.

No. 22,677.

Patented Jan'y 18, 1859.

Fig. 4.

Fig. 1.

UNITED STATES PATENT OFFICE.

SOLOMON SHETTER, OF ALLEGHENY CITY, PENNSYLVANIA.

HORSESHOE-MACHINE.

Specification of Letters Patent No. 22,677, dated January 18, 1859.

To all whom it may concern:

Be it known that I, SOLOMON SHETTER, of the city and county of Allegheny, in the State of Pennsylvania, have invented a new and Improved Machine for Making Horse-shoes; and I do hereby declare that the following is a full and exact description thereof, reference being had to the accompanying drawings and to the letters of reference 10 marked thereon, similar letters referring to similar parts.

The nature of my invention consists in an arrangement of a sliding table, roll, shears, swage, levers, cams, springs, clamps, dies, 15 friction rollers, and lifter, all of which are arranged and combined as hereafter described for the purpose of making horse shoes.

To enable others skilled in the art to make 20 and use my invention I will proceed to describe its construction and operation.

In the accompanying drawings Figure 1, is a side view in outline of the machine, Fig. 2, is an end view of the machine, Fig. 3, is a 25 top view of the machine, Fig. 4, is a top view of the table, with its clamps, springs, lifter, dies and the underpart of the shears.

(a) is the frame of the machine, (b) is the supporting frame for the table (c). (c¹) 30 is a rack which is placed on the under side of the sliding table (c). (d¹) is a cog-wheel which gears into the rack (c¹). (t¹) is a roll, (g) is a cross-bar or guide for the swage (f). (h) is a cross bar or hanger for 35 the shear (d). (e) is the lever which operates the swage (f). (e¹) are the trunnions of lever (e). (j) and (k) are cog-wheels. (l) and (o) are cranks. (m) is a connecting rod which connects the cranks (l) and (o). 40 (y) is the crank to which the power is attached. (q) and (r) are cams which operate the shears (d) and the lever (e) and the swage (f). (u) is the clearer and (n) is the flexible strip which operates it. (n¹) are 45 journal caps. (t) and (w) are dies. (v) is the under-part of the shears (d). (x) are springs. (s) are clamps. (2) are friction rollers. (o¹) is a plate which is attached to the cross-bar (x¹) and is used for the purpose of holding the iron in its place while 50 being bent into the desired shape by the clamps.

I will now proceed to describe the use of the various parts, and their connection the 55 one with the other, and also their operation, (the parts named are arranged in the ma-

chine as represented in the drawings, but the size and mode of making them is left to the judgment of the mechanic.) The supporting frame (b) is secured to the frame (a); 30 the sliding table (c) is moved backward and forward by the rack (c¹) and the wheel (d¹) on the shaft (18); it will be observed that the table is held down and to its place by the shape of the slides, which are plainly represented in Fig. 2 of the drawings; to the table (c) is attached the springs (x), clamps (s), dies (t and w), lifter (u), and the underpart of the shears (marked v), all of which are seen in Fig. 4 of the drawings; 35 the die (w) forms the toe, the die (t) forms the inside edge, the clamps (s) forms the outside edge, and the table (c) and roll (t¹) forms the upper and lower side of the shoe, and the springs (x) prevents clamps from 40 leaving their place and also from coming in contact with the dies; the clamps (s) are opened and closed by the backward and forward movements of the table which brings the curve (w¹) of the clamps (s) in contact 45 with the friction rollers (2); the roll (t¹) on the shaft (5) is moved by the wheels (j and k); the shears (d) and the swage (f) with its lever (e) are operated by the cams (q and r) on the shaft (8). The desired 50 movements of the table (c), roll (t¹), shears (d) swage (f) clamps (s) and clearer (u) are obtained by the arrangement of the cams (q and r), the flexible strip (n) and slot (z) in the connecting rod (m); the cams (q and r) and the flywheel (p) are arranged 55 on shaft (8) as represented in Fig. 3. The clearer (u) is let into the table (c) and is operated by the flexible strip (n), and is used for the purpose of clearing the shoe 60 from the dies after it is formed.

The operations of my improvement are as follows: When all things are arranged as represented by the drawings and as set forth in the specification, I take iron of the proper size, heat it properly and feed it into the machine, passing it under the shear (d) and between the dies (t) and (w) where it is cut into the proper length; it is then bent around die (t) by clamps (s), the clamps being operated by means of the forward movement of the table (c), and by the curved arms (w¹) of the clamps (s) coming in contact with the friction rollers (2), it then passes under the roll (t¹) which is operated by the wheels (j and k), the holes are 65 then punched and the recess made in the 70

bottom face of the shoe for the heads of the nails by the swage (*f*), then by the backward movement of the table (*c*) the clamps (*s*) are opened and the shoe is lifted from 5 between the dies (*t*) and (*w*) by the clearer (*u*) which is operated by the flexible strip (*n*), the machine is then ready for forming another shoe. It will be observed that the iron is cut into proper lengths, bent around 10 the die, properly swaged and punched, the surfaces smoothed by the roll and the shoe completely formed by one revolution of the crank (*y*).

Having thus described my improvement 15 and its operations what I claim as of my invention and desire to secure by Letters Patent of the United States is:

1. The curved arms (*w¹*) of clamps (*s*) moved and operated by the friction rollers 20 (*2*) and the backward and forward move-

ments of table (*c*) when the clamps (*s*) are used in connection with the dies (*t*) and (*w*) as herein described and for the purpose set forth.

2. The use of the flexible strip (*n*) for the 25 purpose of operating the clearers (*u*) as herein described and for the purpose set forth.

3. The arrangement on the upper surface 30 of the table (*c*) of dies (*t* and *w*), springs (*x*), the under jaw (*c*) of the shears and the clearer (*u*) when used and operated in connection with the clamps (*s*), friction rollers (*2*), roll (*t¹*), shear (*d*) and swage (*f*) as herein described and for the purposes set 35 forth.

SOLOMON SHETTER.
